UNITED STATES PATENT OFFICE.

WILLIAM CAMPBELL BONTHON, OF ATLANTA, GEORGIA, ASSIGNOR TO AMERICAN CAN COMPANY, OF NEW YORK, N. Y., A CORPORATION OF NEW JERSEY.

TAG MARKING AND FORMING MACHINE.

1,086,583.

Specification of Letters Patent.

Patented Feb. 10, 1914.

Application filed October 31, 1910. Serial No. 589,889.

To all whom it may concern:

Be it known that I, WILLIAM CAMPBELL BONTHON, a citizen of the United States, residing in Atlanta, in the county of Fulton and State of Georgia, have invented a new and useful Improvement in Tag Marking and Forming Machines, of which the following is a specification.

My invention relates to improvements in machines for marking or lettering and forming or folding sheet metal tags such as are commonly attached to cotton bale ties.

The object of my invention is to provide a machine of a simple, efficient and durable construction, by means of which sheet metal tags may be rapidly and cheaply marked or lettered and folded or formed ready for application to cotton bale ties or other articles.

20 My invention consists in the novel construction of parts and devices and in the novel combinations of parts and devices herein shown and described and more particularly specified in the claims.

25 In the accompanying drawing forming a part of this specification, Figure 1 is a side elevation of a tag marking and forming machine embodying my invention. Fig. 2 is a detail elevation, showing the marking and forming or folding dies closed. Fig. 3 is a horizontal section on the line 3—3 of Fig. 2. Fig. 4 is a detail cross section on line 4—4 of Fig. 2. Fig. 5 is a detail cross section on line 5—5 of Fig. 2. Fig. 6 is a 30 detail plan view of the lower marking and forming dies and the bed or bolster of the press. Fig. 7 is a longitudinal section on line 7—7 of Fig. 6, and Fig. 8 is a perspective view of the formed tag.

40 In the drawing, A represents the frame of the machine, B a reciprocating slide mounted thereon in an inclined position, such as is customarily employed in punching or stamping presses, and C C¹ a crank shaft and pitman for operating the slide.

45 D is the upper or male lettering or marking die carried by the punch slide, the same being preferably furnished with removable marking or lettering type d, secured in the chase d¹ by clamp screws d², the chase being furnished with one or more division bars d³.

E is the inclined bed or bolster of the

press to which is secured the female marking or lettering die F which is preferably furnished with removable marking or lettering type f secured in the chase f¹ by clamp screws f², which is furnished with one or more division bars f³ according to the number of lines the lettering or marking of the tag X may require. The lower die F is further provided with a stop or registering pin f⁴ to register and hold the tag X on the inclined lower die.

55 The punch or reciprocating die D carries a pivoted pawl or hook shaped extractor G, fitting in an upright, transverse slot in one side of the die D, adapted to enter a corresponding slot f⁵ in the lower or female die F and engage the head x of the sheet metal tag X, and lift the same above the upper end of the stop pin f⁴ on the upward stroke of the punch, and thus permit the marked or lettered tag X to slide down the bed or lower die into registry with the male and female folding or forming dies H, K. The lower or female folding or forming die K has a longitudinally extending slot or opening k, through which the tag X may be punched or forced by the male or blade-like folding or forming die H, the same preferably having an inclined edge h to cause the folding or forming operation to be performed gradually or progressively. The upper or male folding die H is carried 60 by a lever H¹, pivotally connected at h¹ to the lower or bed die F and adapted to be engaged by pins or projections d⁴ on the upper die or punch D as the latter descends. The lever H¹ is preferably of bail form, its arms h² fitting astride the male die or punch D. To cause the male forming die H to be lifted on the upper stroke of the punch D, its operating lever H¹ is connected therewith by coiled springs h³, the upper ends of which engage pins or projections d⁴ on the punch, and the lower ends of which engage pins or projections h⁴ on the folding die operating lever H¹. The operating lever H¹ gives to the male folding die H 65

90 preferably about twice the movement of the punch, thus enabling the male folding die to properly perform its function, which, on account of the size of the tag, requires a somewhat extended movement, while at the same time the marking or lettering die D 95

may have a relatively short stroke and thus be adapted for rapid action and the greater power required for the lettering or marking operation.

5. The lower or female folding die K is furnished with a stop pin or projection K¹ adapted to engage the head *x* of the sheet metal tag X, and thus register and hold the same in position on the inclined bed for receiving the operation of the folding dies.

10. The blade of the male folding die H is made deep enough and the stroke thereof is sufficiently extended to carry the folded tag X through the female folding die K and thus discharge the same from the machine or press.

15. In operation, the sheet metal tags X in the flat are first fed into position between the male and female marking or lettering dies D, F, the head *x* of the tag X resting against the stop *f*¹, thus holding the tag in position on the inclined lower die until the upper die descends. On the upstroke of the upper die, the depending hook shaped 20 extractor G, the hook *g* of which has been depressed below the tag X by the down stroke of the punch D, engages the marked or lettered tag X at the head *x* thereof and lifts the same above the stop *f*¹, thus permitting the tag to descend by gravity 25 against the stop K¹ of the lower folding die K. Simultaneously with the downstroke of the lettering die D, the upper folding die H descends and folds the preceding tag upon itself by forcing it through the slot *h* of the lower folding die and thus discharging the tag from the machine. On the upstroke of the punch D, the upper or male folding die H is lifted through the 30 spring connection of its operating lever with the upper die D. Two tags are thus simultaneously operated upon in the machine, one by the male and female marking or lettering dies, and the preceding one by the folding 35 dies, one tag being both lettered and folded at each stroke of the press.

40. The hook shaped extractor G is provided with a spring *g*¹ to hold it in position to engage the head *x* of the tag and permit it to retract and pass the tag on the down stroke of the die D, the extractor having an inclined or cam face *g*² to guide it past the head of the tag.

45. I claim:—

50. 1. In a tag marking and folding machine, the combination with upper and lower marking dies, of upper and lower folding dies and a lever for operating the movable folding die from the movable marking die and simultaneously imparting to the folding die a movement greater than that of the marking die, substantially as specified.

55. 2. The combination with an inclined lower marking die, of an inclined lower folding die below the marking die, an upper

reciprocating marking die and a swinging folding die having a lever engaged and operated by the upper marking die, substantially as specified.

3. In a tag marking and folding machine, 70 the combination with upper and lower marking dies, of upper and lower folding dies; and a lever for operating the movable folding die from the movable marking die, and simultaneously imparting 75 to the folding die a movement greater than that of the marking die, said lower marking die having a stop to engage the tag, and said upper marking die having a hook shaped extractor adapted to engage the tag 80 and lift the same above said stop on the upstroke of said upper die, substantially as specified.

4. The combination with a fixed marking die, of a fixed folding die, a movable marking die, a movable folding die, and a bail lever pivotally connected to the fixed marking die and carrying said movable folding die, the arms of said bail lever embracing the movable marking die, substantially as 85 specified.

5. The combination with a fixed marking die, of a fixed folding die, a movable marking die, a movable folding die, and a bail lever pivotally connected to the fixed 95 marking die and carrying said movable folding die, the arms of said bail lever embracing the movable marking die, said movable marking die having projections at its sides engaging the arms of said bail lever, 100 substantially as specified.

6. The combination with a fixed marking die, of a fixed folding die, a movable marking die, a movable folding die, and a bail lever pivotally connected to the fixed 105 marking die and carrying said movable folding die, the arms of said bail lever embracing the movable marking die, said movable marking die having projections at its sides engaging the arms of said bail lever, 110 and connections between said bail lever and said movable marking die to raise said movable folding die on the upstroke of the movable marking die, substantially as specified.

7. The combination with a stationary 115 marking die having a type chase and marking die type, of a movable marking die having a type chase and marking die type, of a stationary folding die having a slot, a movable folding die having a blade and a 120 lever hinged to said stationary marking die and carrying said movable folding die, said movable marking die having a pin engaging said lever to operate the movable folding die, substantially as specified.

8. In a machine of the character described, in combination: two sets of dies, each set comprising a stationary and a co-operating movable die; a lever between the movable dies for operating one movable die 130

by the other; a stop on one of the fixed dies has been operated upon, substantially as adapted to properly position the article specified.
being operated upon; and a hook shaped extractor carried by the movable die coöperating with said fixed die having the stop, the extractor being adapted to remove an article from between the dies after the same

WILLIAM CAMPBELL BONTHON.
